COMBINED LAMP AND MIRROR

Dan M. Andre, 8843 Kostner Terrace, Skokie, Ill. 60076

Filed Nov. 18, 1966, Ser. No. 4,732

Term of patent 14 years

(Cl. D48—20)

FIG. 1 is a perspective view of a combined lamp and mirror illustrating my new design;

FIG. 2 is a perspective view of my lamp with the shade and mounting pole in the collapsed position;

FIG. 3 is a side elevational view of my lamp in the extended position, as illustrated in FIG. 1;

FIG. 4 is a top plan view of the same;

FIG. 5 is a front elevational view of the same; and

FIG. 6 is a rear elevational view of said lamp.

The surface shading on the annular band exterior of the reflective surface in FIGS. 1 and 5 is representative of a refractive lens pattern and is understood to be continuous throughout said band.

I claim:

The ornamental design for a combined lamp and mirror, substantially as shown and described.
